UNITED STATES PATENT OFFICE.

EUGENE M. WEAVER, OF OZONE PARK, NEW YORK.

SIGNAL SYSTEM FOR RAILWAY-CROSSINGS.

1,179,987.

Specification of Letters Patent. Patented Apr. 18, 1916.

Application filed October 31, 1908, Serial No. 460,493. Renewed September 18, 1915. Serial No. 51,113.

To all whom it may concern:

Be it known that I, EUGENE M. WEAVER, a citizen of the United States, and a resident of Ozone Park, county of Queens, State of New York, have invented certain new and useful Improvements in Signal Systems for Railway-Crossings, as set forth in the following specification.

This invention relates to signaling systems and apparatus for railway crossings.

An object of the invention is to provide suitable apparatus and a suitable system for the giving of a danger signal at the crossing upon the approach of a railway train and at 15 a time sufficiently before the train reaches the crossing to give ample warning to persons about to cross the railway.

It is a further object to maintain a continuously operating audible danger signal 20 until the train has reached the crossing. It is a still further object of the invention to provide for the giving of such a signal both for the approaching in-running and for the approaching out-running trains and to prevent 25 the repetition of such a signal from the unavoidable contact of a part of the train with a track or trolley instrument which train has passed the crossing and has once given a signal upon approaching the 30 crossing.

A further object is to accomplish the operation of a signal for a crossing, which signal may be of any approved type audible or visible, in such a manner that, when a train 35 approaching the crossing reaches a pre-determined point, the signal will operate, and to maintain the operation of said signal for a minimum period after the train has reached said point whether or not said train 40 may be almost immediately following a previous train approaching the crossing. Thus it is an object to accomplish the above maintenance of signal operation for a minimum period independently of whatever the period 45 of operation of any actuating means at the track may be.

A further object of the invention is to provide for the testing of the various circuits at a convenient locality and in such a 50 manner that the circuits must be restored to their normal conditions after such a test has been made by an inspector.

A further object of the invention is to provide an improved time bell mechanism, an 55 improved time circuit closer and an im-

proved trolley instrument for actuation by moving trains.

A special object in connection with the trolley instrument is to provide mechanism which will operatively energize a certain circuit when the instrument is actuated by a train running in one direction but which will be inoperative to close said circuit when actuated by a train moving in the opposite direction.

It is still a further object of the invention to improve in general the apparatus for use in connection with crossing signaling systems.

The above and further objects of the invention will be set forth in the accompanying claims and will be clear from the following description, which may be read in connection with the accompanying drawings which form part of this application, in which like characters designate corresponding parts, and in which,

Figure 1 is a diagram showing the installation of the system applicable to trolley railways; Fig. 2 is a front elevation showing the time bell in detail; Fig. 3 is a side elevation of the parts shown in Fig. 2; Fig. 4 is a rear elevation with the base removed showing the test box; Fig. 5 is a side elevation of the test box partly in vertical section 80 and with parts broken away; Fig. 6 is a vertical section through the trolley instrument, parts being shown in elevation; Fig. 7 is a plan view of the parts shown in Fig. 6 with the cover removed. Fig. 8 is a cross section 85 through the parts 3, 57 and 144 of Figs. 6 and 7; Fig. 9 is a perspective view of the latch mechanism for the time bell with the parts in their relative position for the plate 108 released by shoulder 118 and resting on 90 shoulder 119; and Fig. 10 is a view similar to Fig. 9, but showing the parts in their relative positions for the plate 108 released by both shoulders 118 and 119 and resting 95 upon ledge 121.

Referring now more in detail to the drawings, 1 indicates a grade crossing for the railway 2. In Fig. 1 is a trolley railway, the trolley wire being indicated by 3. The arrows 4 indicate what may be termed the in-running direction, while the arrows 5 indicate what may be termed the out-running direction.

In the installation shown in Fig. 1 a source of electro-motive force connected be- 110

tween the trolley wire 3 and the rails 2 serves as the source of electro-motive force for the operation of the system. In this installation two trolley instruments 54 and 55 are provided and located so that 54 is at a suitable distance in advance of the crossing 1 to in-running trains and so that 55 is at a suitable distance in advance of the crossing 1 to out-running trains. In this installation the time bell 15 is located adjacent to the crossing 1. One test box 21 may also be provided. The trolley wheel 56 of an in-running train is shown diagrammatically in the figure and is electrically connecting trolley wire 3 with contact strip 57 of trolley instrument 54, which strip is itself a train actuated instrument. For this installation the in-running actuating circuit may be traced as follows:—trolley wire 3, contact strip 57, connection 58, contact 59, bridge 60, contact 61, wire 62, wire 63, holding magnet 17, wire 64, resistance 65, to ground 66 and thence to rail 2. This circuit is normally open although shown closed by wheel 56.

The normally open out-running actuating circuit may be traced as follows:—trolley wire 3, contact strip 57', connection 58', contact 59', bridge 60', contact 61', wire 67, wire 68, wire 63, holding magnet 17, wire 64, resistance 65, to ground 66, thence to rails 2.

The testing circuit may be traced as follows:—trolley wire 3, wire 69, wire 70, test box 21, wire 71, wire 68, wire 63, magnet 17, wire 64, resistance 65, to ground 66, etc. This circuit is normally open.

The normally open operating circuit or bell ringing circuit may be traced as follows:—trolley wire 3, wire 69, wire 72, vibratory circuit breaker 39, wire 73, magnet 18, wire 74, front contact 75, armature 37, wire 76, wire 64, resistance 65, to ground 66, etc.

Apparatus—Time bell.—The expression “time bell” is used in this specification to designate such an apparatus as is illustrated in Figs. 2, 3, 9 and 10, the circuit connections for which have previously been described in connection with Fig. 1. This apparatus comprises an operating or bell ringing magnet 18 of suitable construction mounted on a suitable base 77. The bell clapper armature 78 is pivoted to a bracket 79 secured to base 77. A retracting spring 80 may also be secured to the bracket 79 and tend to retract the armature 78 through the medium of the bail 81. The spring 80 also serves with the spring 82, suitably mounted on an insulated post 83, as a vibratory circuit breaker indicated as a whole by 39. The above enumerated parts of the time bell constitute the audible signal and electromagnetic mechanism for operating the same.

Suitably secured to the armature 78 is an

extension 84 extending upwardly beyond the pivot 85 a suitable distance. A laterally extending arm 86 is hinged to the extension 84 by the hinge 87 and is normally pressed downwardly, as by gravity or by the spring 88 or by both gravity and the spring. The extreme end of arm 86 is provided with a hook 89 serving as a pawl for engagement with the ratchet teeth 90 of ratchet wheel 91 fixed to shaft 92, suitably mounted in a frame 93 carried by the base 94, to which may be secured the base 77 or a part of which base the base 77 may be. Also fixed to shaft 92, is a pinion 95 intermeshing with gear 96 fixed to shaft 97 also pivoted in frame 93. The pinion 95 and gear 96 serve as reduction gearing, the ratio of which may be arranged as desired. It has been found that twenty-four teeth for pinion 95 to 72 teeth for gear 96 are satisfactory. Adjustably secured to the shaft 97 in different vertical planes, are two cams 98 and 99. The set screws 100 and 101 may serve as means for thus adjustably securing these cams.

The stroke of the pawl 89 may be regulated to a degree by means of the screws 102 and 103 operating upon the armature 78. Independently of the screws 102 and 103 the stroke of the pawl 89 effective upon the teeth 90 of ratchet wheel 91 may be regulated by the adjustable wedge barrier 104. This wedge barrier may be mounted upon a standard 105 adjustably secured to the frame 93, as by means of the screw 106 passing through a suitable slot in the standard 105. The free end of the barrier 104 is downwardly inclined forming a cam surface over which the pawl 89 must move so as to disengage the pawl from the ratchet teeth 90. By adjusting the barrier 104 one reciprocation of the pawl 89 may be made to step along the ratchet wheel one, two, three, or more teeth at will. It should be understood that sufficient friction or a suitable checking means is present in the gear mechanism to permit a movement of this gearing only in its forward direction. The above latch and ratchet mechanism constitutes means for maintaining the operation of the audible signal for a definite period after the last actuation of the holding or actuating magnet 17.

17 indicates the holding magnet for the time bell and it may be of any well known suitable construction. Its armature 37 is suitably pivoted to bracket 107 which may be mounted upon base 94. The armature 37 carries an electrically conducting member 108 insulated from armature 37 as indicated and having a suitable circuit connection 109 near its right hand end. If desired an adjustable counter-balance weight 110 may be provided to reduce the effective turning moment of the armature parts about the hinge 107. The free end of the part 108

is shown provided with a spring contact piece 111 for coöperating with the front contact 36 which may preferably be a carbon contact carried in the adjustable holder 112, 5 suitably supported but insulated from the frame 113 secured to base 94. Also secured to the frame 113, insulated and depending therefrom, is a stirrup frame 114, extending down through a suitable opening in the plate 108. Within and pivoted to the stirrup frame 114 by means of the pin 115 are two latch members, 116 at the rear, and 117 at the front. The depending ends of these latch members extend down into the path of and 10 coöperate with the cams 98 and 99 respectively. When the parts are in the holding position shown, the shoulder 118 of latch member 116 engages under the lower edge of plate 108. Slightly below the shoulder 20 118 there is provided a shoulder 119 on latch member 117 which is capable of engaging against the under surface of plate 108 when the shoulder 118 is removed. Spring means such as 120 secured to stirrup frame 114 25 may be provided normally to press latch members 116 and 117 into the position illustrated in Figs. 2, 9 and 10. It should, of course, be understood that the relative positions of latch members 116 and 117 and the 30 corresponding cams 98 and 99 may be reversed if desired.

The parts are shown in holding position. The operating engagement of cam 98 with latch member 116 permits plate 108 to fall 35 upon shoulder 119 and shoulder 118 remains out of holding position (see Fig. 9 in which the dotted lines show the plate 108 resting on shoulder 119 and holding out the latch 116 against the action of spring 120.) The 40 subsequent engagement of latch member 117 by cam 99 upon a complete rotation of gear 96 removes shoulder 119 from holding engagement with plate 108 which plate then falls against ledge 121 (see Fig. 10) of stirrup frame 114 and contact 111 breaks contact 45 with front contact 36. Up to this time contact between 111 and 36 was maintained. The parts are actually shown in operating positions with the bell supposed to be ringing. It is to be understood, however, that 50 the normal position is substantially the same as that indicated for the gears but that the armature 78 would be retracted and the plate 108 would be resting upon shoulder 55 121. The energization of magnet 17 lifts up armature 37 which carries plate 108. The latch members 116 and 117 are forced to the right by spring means 120 so that shoulders 118 and 119 pass under the lower 60 face of 108 to hold contact 111 in contact with front contact 36.

At this point particular attention is called to the fact that two latches 116 and 117 with their respective shoulders 118 and 119 are 65 provided for the circuit closing armature

37 and that each latch has its own coöperating cam 98 and 99 respectively, which cams are angularly displaced as indicated. Either the shoulder 118 or the shoulder 119 by engaging with the under face of plate 108 or 70 an equivalent part is sufficient to hold the contact 111 closed against front contact 36.

The purpose of the plurality of latches will be apparent to those skilled in the art if it is borne in mind that not infrequently 75 the railroad may have a plurality of tracks over which a plurality of trains may be approaching the crossing fairly close together. It would, of course, be highly dangerous for the first train merely to give a 80 warning signal and then for the signal to cease operating long before the last train approaching the crossing had reached the crossing. It is to prevent this occurrence

that the plurality of latches and their coöperating parts are provided. Suppose the first train has actuated the parts so that they assumed the positions shown in Fig. 2. A short time afterward and before this train had reached the crossing, cam 98 85 90

would have caused shoulder 118 to release plate 108 but shoulder 119 would still be holding the plate so as to hold the operating circuit closed. If a second train did not actuate magnet 17 a second time the cam 95 99 would complete its rotation and release shoulder 119 from plate 108 to effect the opening of the operating circuit. On the other hand if the second train should actuate magnet 17 shortly after cam 98 had 100

operated upon latch 116, the magnet 17 would then lift the plate 108 so as to cause shoulder 118 to reengage the plate and hold it in the position indicated in Fig. 2. The continued rotation of the cams would bring 105

cam 99 into engagement with latch 117. This latch would move into releasing position but could not release plate 108 as this plate would then be held by latch 116. Latch 117 would then spring back into the position 110

shown in the drawing ready to engage and hold the plate 108 in proper position when the cam 98 engaged the latch 116 on its second rotation. The bell 122 would then be 115 continuously ringing for a definite minimum period, that is, until the cam 99 had made its second rotation and had released latch 117. Thus it is evident that the apparatus provides for the continuous operation of the danger signal throughout a pre-determined interval of time for the last train which may be approaching the crossing notwithstanding the fact that said last train may be immediately following a preceding train. It is to be understood also 120

that a plurality of trains might follow one another at short intervals on a single track road as well as on one having a plurality of tracks. It is also contemplated that the time mechanism described need not of necessity 125

120

125

130

be electro-magnetic or that it be used as a bell sounding mechanism.

By varying the effective operating stroke of pawl 89, the time of operation or ringing of the bell 122 may be regulated as desired. It is to be understood that any approved manner of effecting the circuit connections as, for example, that illustrated in diagram in Fig. 1 may be provided in the apparatus shown in Figs. 2, 3, 9 and 10. It is also to be understood that the embodiment illustrated and described is merely for the purpose of illustration and that suitable changes in construction to satisfy varying conditions are contemplated.

In Figs. 4 and 5 one embodiment of a test box is illustrated with the parts shown in such relative positions as to effect a test of the operation of a circuit. The apparatus electrically comprises two stationary contacts 123 and 124 which may be secured to a suitable base 125 and a movable contact 126 secured to and insulated from a shaft 127 suitably journaled in the cover portion 128 and provided with an operating handle 129. Also secured to the shaft 127 is a stop disk 130. A ring segment is cut out of the disk 130 between stops 131 and 132 leaving a circular edge 133. A pocket 134 is provided in the edge 133 capable of receiving the lower end of bolt 135. In the position shown the lower end of bolt 135 rests on the circular edge 133 and the same is pressed down by spring 136 and guided in its movement by guides 137 and 138 secured to cover portion 128. A key hole 139 of any desired configuration to correspond to the key used is provided in the cover portion 128. The operating key is indicated by 140 after having been passed through the key hole 139. The key is centered by bracket 141 and its stub co-operates with shelf 142 to lift the bolt 135 into the position indicated. When the bolt is moved into the position indicated it has been retracted from the pocket 134 and the handle 129 may be manipulated to move the contact 126 across the contacts 123 and 124. A ledge 143 is provided on the bolt 135 in the returning path of the stub of key 140 so as effectually to prevent the removal of key 140 until the handle 129 has been manipulated so as to cause the bolt 135 to shoot into the pocket 134 which locks the parts so that the contacts are normally open. By this provision it is impossible for an inspector to leave the bridge connection 126 across contacts 123 and 124 to cause a shunt in the operating circuit to endanger the circuit operation or cause false or faulty indication in response to train movements.

A satisfactory embodiment of the trolley instruments illustrated in diagram in Fig. 1 is shown in detail in Figs. 6 and 7. The apparatus is shown in the same position

70 relatively to the trolley wire 3 as is the trolley instrument 54 illustrated in diagram in the figure referred to. In this instrument an insulating plate or board 144 is arranged parallel to the trolley wire 3 and with its sides inclined from the vertical as indicated. This board may be suitably supported in any approved manner as by over head brackets 145 and 146 held up by guy wires 147 and 148. Secured along the inside edge of the board 144 is a trolley wheel contact strip 57 of suitable conducting material at such a distance from the trolley wire 3 that the trolley wheel will serve to bridge from the trolley wire to this strip in its normal passage along the wire. Suitably secured to the board 144 as by a frame 150 is an insulating base 151. Mounted upon the base 151 is a suitable circuit breaker which may be of the form shown comprising two contacts 59 and 61 which may be provided with carbon tips 152 and 153. A suitable bridge contact 60 normally electrically connects contact 59 with contact 61 and a suitable connection as indicated in Fig. 1 80 may be provided between strip 57 and contact 59. Bridge contact 60 is carried by but insulated from a yoke 154 extending from and secured to the piston 155 of dash pot 156 which is provided with a quick intake but slow exhaust valve 157. The bridge 90 95 100 105 110 115 120 125 contact 60 and yoke 154 and the dash pot piston 155 are normally held in the position illustrated by the compression spring 158 which is illustrated located about the guide rod 159 forming an extension for the yoke 154 and passing through the bracket 160 suitably secured to the base 151. A forked striker member 161 normally straddles the trolley wire 3 in position to be struck by the trolley wheel during its passage along the wire 3. This member 161 is hinged as by pin 162 to the bracket 163 secured to the base 151. An upwardly extending arm 164 which may be integral with member 161 extends through the yoke 154 and provides an operating cam surface 165 for co-operating with the roller 166 pinned by pin 167 to yoke 154. A hood 168 of sheet metal or other suitable material may serve as a canopy for the parts described and may be suitably secured to the board 144, which may be of any desired length.

A trolley wheel traversing the wire 3 from left to right will serve to connect the trolley wire to contact strip 57 in a well known manner and in turn energizes contact 61 through the medium of the bridge 60 and contact 59. This energization will be maintained for a certain interval of time according to the length of the strip 57, and is of sufficient duration to cause the operative energization of the actuating circuit. However, the effect of a trolley wheel moving from right to left in an out-running

direction is different; the wheel first engages the fork 161 throwing the same to the left and causing the cam 165 to move the yoke 154 to the right against the spring 158. This movement is not materially retarded by the dash pot 156. The restoration of the parts to normal positions indicated is, however, slow due to the retarding effect of the dash pot. The parts are so designed that the 10 trolley wheel will have passed over and beyond the contact strip 57 while the bridge 60 is out of contact with contacts 59 and 61 and, of course, before the spring 158 has restored the bridge 60 to its normal bridging 15 position. Thus the trolley instruments are organized so as operatively to energize the actuating circuits only in response to a train moving in one direction. They are arranged in Fig. 1 so as to operatively energize the 20 respective actuating circuits only in response to trains approaching the crossing, not in response to those leaving the crossing. This avoids false signals.

Operation.—An in-running train first 25 actuates the track instrument which operatively energizes the in-running actuating circuit causing magnet 17 to pick up its armature 37, which closes the operating circuit for the time bell. The energization 30 of magnet 17 is short but its armature is held up by latches 116 and 117. The bell continues to ring until the train has nearly reached the crossing when the cam 99 actuates the latch 117 to release the armature 37 and open the operating circuit for 35 the bell. The cam 98 has previously actuated latch 116 to release its hold on the armature 37.

The train actuated instruments are placed 40 at two localities and are shown as trolley instruments 54 and 55. The trolley instrument 54 has means rendering it operative for energizing the in-running actuating circuit only by in-running trains. Instrument 55 is the same for out-running trains and the out-running actuating circuit.

The operation of the test boxes has been described in the specific description of the same. Although they have been shown of 50 the normally open circuit type, it is contemplated that merely a re-adjustment of their contacts would adapt them for normally closed circuit work. They may be located at any desirable locality and connected into 55 any circuit which it may be desired to have easily tested.

Although preferred embodiments of the invention have been illustrated and described, it is to be understood that all modified arrangements possible are contemplated and the apparatus may be altered within the spirit of the invention.

What is claimed and what is desired to be secured by United States Letters Patent is:

65 1. In a signaling system for railway cross-

ings, a holding magnet; actuating circuit connections for said magnet; a circuit closing armature for said magnet; a vibratory electric bell in circuit with said circuit closing armature; a pawl reciprocated by the 70 armature of said vibratory bell; a plurality of latches in coöperative relation with said circuit closing armature and capable of holding the same in closed position; a ratchet wheel operated by said pawl, and a plurality 75 of cams operated by said ratchet wheel, one for each latch and operative to release the latches from said circuit closing armature.

2. In a signaling system for railway crossings, a holding magnet; actuating circuit 80 connections for said magnet; a circuit closing armature for said magnet; a vibratory electric bell in circuit with said circuit closing armature; a pawl reciprocated by the armature of said vibratory bell; a plurality 85 of latches in coöperative relation with said circuit closing armature and capable of holding the same in closed position; a ratchet wheel operated by said pawl; means 90 for adjusting the effective stroke of said pawl independently of the stroke of said vibrating armature; and a plurality of cams operated by said ratchet wheel, one for each latch and operative to release the latches from said circuit closing armature. 95

3. In a signaling system for railway crossings, a holding magnet; actuating circuit connections for said magnet; a circuit closing armature for said magnet; a vibratory electric bell in circuit with said circuit closing armature; a pawl reciprocated by the 100 armature of said vibratory bell; a plurality of latches in coöperative relation with said circuit closing armature and capable of holding the same in closed position; a ratchet wheel operated by said pawl; means 105 for adjusting the effective stroke of said pawl independently of the stroke of said vibrating armature; and a plurality of rotating cams adjustable in their relative positions and operated by said ratchet wheel, one for each latch and operative to release the latches from said circuit closing armature. 110

4. In a time-crossing-signal-mechanism 115 an electric annunciator; a normally open circuit closer for said annunciator; train controllable means for closing said circuit closer; a plurality of latches, each independently operative to hold said circuit closer closed; a plurality of rotatable latch-releasing cams, one for each of said latches and spaced apart in operative relation to said latches; means for rotating said cams commensurately with the operation of said annunciator; and provisions to effect the opening of said circuit closer, only by the release of said latches in complete sequence after the operation of said train controllable 120 means. 130

5. In a time electro-magnetic mechanism, an operating electro-magnet; a circuit closer for said operating electro-magnet; an actuating electro-magnet for operating said circuit closer; latching means for holding said circuit closer closed independently of said actuating magnet; means for releasing said latching means and operable by said operating magnet; and provisions for preventing the complete release of said circuit closer until a minimum time interval has elapsed after the energization of said actuating electro-magnet.
10. In a time electro-magnetic mechanism, an operating electro-magnet; a circuit closer for said operating electro-magnet; an actuating electro-magnet for closing said cir-
15. In a time electro-magnetic mechanism,

cuit closer; a plurality of independently movable latches for holding said circuit closer closed; a plurality of angularly displaced cams for releasing the respective latches; means for rotating said cams commensurately with the operation of said operating electro-magnet; and provisions for effecting the complete release of said circuit closer only when said latches are released in a predetermined order.

In testimony whereof, I have signed my name to this specification, in the presence of two subscribing witnesses.

EUGENE M. WEAVER.
